CLAIM

We claim the ornamental design for a machine for regulating the temperature, aeration and distribution of wine, as shown and described.

DESCRIPTION

1. Machine for regulating the temperature, aeration and distribution of wine

1.1 : Perspective

1.2 : Front

1.3 : Back

1.4 : Right

1.5 : Left

1.6 : Top

1.7 : Bottom

1.8 : Perspective
